(57) **CLAIM**

The ornamental design for a hood for use with chairs, as shown and described.

DESCRIPTION

FIG. 1 is a front upright view of the hood;

FIG. 2 is a front recline view of the embodiment shown in FIG. 1;

FIG. 3 is a left upright view of the embodiment shown in FIGS. 1-2;

FIG. 4 is a left recline view of the embodiment shown in FIGS. 1-3;

FIG. 5 is a right upright view of the embodiment shown in FIGS. 1-4;

FIG. 6 is a right recline view of the embodiment shown in FIGS. 1-5;

FIG. 7 is a top upright view of the embodiment shown in FIGS. 1-6;

FIG. 8 is a top recline view of the front of the embodiment shown in FIGS. 1-7;

FIG. 9 is a back upright view of the embodiment shown in FIGS. 1-8;

FIG. 10 is a back recline view of the embodiment shown in FIGS. 1-9;

FIG. 11 is a bottom upright view of the embodiment shown in FIGS. 1-10;

FIG. 12 is a bottom recline view of the embodiment shown in FIGS. 1-11;

FIG. 13 is a rotated perspective upright front view of the embodiment shown in FIGS. 1-12; and,

FIG. 14 is a rotated perspective upright back view of the embodiment shown in FIGS. 1-13.
